E. W. ROE

BASKET BALL GOAL

Filed August 17, 1925

INVENTOR.
Everett W. Roe
BY
Albert J. Fiske
ATTORNEY.

UNITED STATES PATENT OFFICE.

EVERETT W. ROE, OF LOUISVILLE, KENTUCKY.

BASKET-BALL GOAL.

Application filed August 17, 1925. Serial No. 50,604.

To all whom it may concern:

Be it known that I, EVERETT W. ROE, a citizen of the United States, residing at Louisville, in the county of Jefferson and State of Kentucky, have invented certain new and useful Improvements in Basket-Ball Goals; and I do hereby declare the following to be a full, clear, and exact description of the invention, such as will enable others skilled in the art to which it appertains to make and use the same.

This invention relates to improvements in basket ball goals and has for its principal object the provision of such a device which when fixed in position on the backboard shall be non-vibratable when struck by the ball, no matter from what position.

Another important object of this invention is the provision of a basket ball goal which shall be simple of construction, readily fixed in position and which when attached shall not be liable to work loose or developing objectionable rattling.

A still further important object of this invention is to provide a device of this sort which will be slightly in appearance, composed of a minimum of parts and so constructed that there will be no possibility of the ball lodging upon the same or becoming wedged between the device and the backboard during play.

Another and further important object of the invention is to provide a substantially circular ring having extensions adapted to be directly attached to the backboard or support but which, when in position will form an unbroken circle as is necessary in devices of this sort.

Other and further important objects of the invention will be apparent from the disclosures in the accompanying drawing and following specification.

The invention, in a preferred form, is illustrated in the drawings and hereinafter more fully described.

In the drawings:

Figure 1 is a top plan view of the improved basket ball goal of this invention.

Figure 2 is a side elevation thereof.

Figure 3 is a rear view showing the means for fixing the same in position.

Figure 4 is a sectional view taken on the line 4—4 of Figure 1.

As shown in the drawings:

55 The reference numeral 10 indicates generally the ring of the device which is com-

posed of malleable iron or any other preferred material.

As shown in the figures, the ring does not form a complete circle but has integral 60 herewith downwardly extending arms or brackets 12. These arms are preferably slightly flattened at their extremities as at 14 and provided with holes 16 for the reception of fastening screws or bolts. As 65 best shown in Figure 2 the arms 12 are first bent at a slight angle to the horizontal ring 10 and then at some distance from the original bend another bend of greater angle is imparted to the arms 12, whereby they will 70 be almost parallel with the backboard or other support 18.

A novel form of combined attaching means and support for the ring 10 and arms 12 is provided in 2 angle irons or the like 75 20 having webs 22 integral herewith. The structure of these angle irons is best shown in Figures 2, 3, and 4 and it will be noted that the rear face of each is provided with openings 24 for the reception of suitable 80 fastening means.

Applied to the upper face of the angle irons or supports 20 are 2 horizontally extending plates 26 and 28 respectively having corresponding depressions therein adapted 85 to receive and maintain in position the arms or extensions 12. Holes are provided in the plates 26 and 28 for the reception of rivets or the like 30 by means of which said plates are securely fastened to each other and to the supporting brackets 20 whereby a rigid and substantial structure is obtained.

As best shown in Figure 1 the outer edges of the plates 26 and 28 are formed by stamping or otherwise in a shape to correspond 90 with the ring 10 and thereby serve to complete the gap formed on account of the particular structure or bend of the arms 12. In this manner the ring 10 is thereby completed and a circular support for the basket is 95 formed, the corresponding stamped out portions of the inner edges 32 of the plates 26 and 28 serving to complete the circle.

The width of the plates 28 and 30 and the upper surface of the brackets 20—22 are so proportioned that there is no possibility of the ball lodging upon or becoming wedged between the goal structure and the backboard.

It will be evident that hereby is provided a particularly rigid structure composed of a minimum of parts and which is so designed

that it will satisfactorily fulfil all the requirements necessary to withstand the strains and stresses to which a device of this sort is ordinarily subjected. Its simplicity of construction renders it readily economically manufactured and it may be assembled and installed with a minimum of trouble and if desired may be readily dismounted and transported from place to place without 10 any fear of any of the parts thereof becoming loose or subject to objectionable vibration.

I am aware that many changes may be made and numerous details of construction 15 varied throughout a wide range without departing from the principles of this invention, and I therefore do not purpose limiting the patent granted hereon otherwise than as necessitated by the prior art.

20 I claim as my invention.

1. A basket ball goal including a ring, extensions integral with said ring adapted to be attached directly to a support and an auxiliary supporting means adapted to cooperate with said extensions, said auxiliary means including a pair of webbed angle irons.

2. A basket ball goal including a ring,

extensions integral with said ring adapted to be attached directly to a support and an auxiliary supporting means adapted to cooperate with said extensions, said auxiliary means including a pair of webbed angle irons and two horizontally extending plates adapted to be attached to said angle irons and to securely clamp said extensions.

3. A basket ball goal including a substantially circular ring, portions of said ring being downwardly and outwardly directed to provide an attaching means, and an auxiliary attaching means so constructed as to complete the gap formed by such downward and outward directed portions.

4. A basket ball goal including a ring, a gap in said ring formed by attaching means integral with said ring and supplementary attaching means adapted to form a complementary portion to fill the gap in the ring.

5. A basket ball goal including a pair of webbed angle iron supports, an incomplete ring and means for attaching the ring to said supports, said means including a pair of plates adapted to complete the contour of the ring.

In testimony whereof I affix my signature.

EVERETT W. ROE.
